CLOSURE FOR PACKING CONTAINERS

Karl Wilhelm Mauser, Waldeck, Bez. Kassel,
GermanyApplication December 20, 1934, Serial No. 758,486
In Germany December 23, 1933

12 Claims. (Cl. 220—61)

Tension ring closures for packing containers are known in many forms as regards a closure means and actuating device. Thus, there are closures with tension screw fixing, eccentric levers, plate securing and the like.

These kinds of closure devices are sometimes too involved in manipulation but mostly are too complicated and therefore are very expensive in manufacture, according to the circumstances.

10 There has hitherto been no suitable tension ring closure which is simply and easily operated, offers a possibility of absolutely certain fastening and also has the advantages of cheapness so that it can also be used in all the cases where 15 it has hitherto been impossible on account of the high cost of manufacture.

According to the invention the tension ring closure is actuated in such a manner that the tension ring is stretched into the closed position by 20 means of pliers, made for this purpose. With this object in view holes are provided at the ends of the tension ring in which the jaws of the pliers engage. Furthermore, the ends of the ring are provided with simple closure members which automatically come into engagement, either by interlocking or catching one behind the other, or 25 are held by being embraced by additional means and thereby securing the tension ring in the closed position.

30 This tension ring closure which allows of various securing means being selected is very cheap in manufacture on account of its simplicity. Consequently it is now possible to use the advantageous tension ring closure for removable covers 35 in all packing containers where its use was formerly excluded on account of the high cost.

Since there are no actuating means secured to the tension ring there are no projections so that 40 the ring closure can serve for rolling. In this case the tension ring may be provided with a reinforcing ridge extending around it. The closure members themselves are protected by the edge of the cover.

45 The invention will be further explained with reference to the constructional examples illustrated in the accompanying drawings. Similar parts have similar references in all figures.

Fig. 1 is a cross-sectional view of my improved 50 closure applied to a receptacle, only a fragment of said receptacle being shown, and said fragment being also in section.

Fig. 2 is a side elevation of the closure shown in Fig. 1, with a portion of said closure and a fragment of the receptacle being shown in section.

Fig. 3 is a view similar to Fig. 2 but showing a modification of my invention.

Fig. 4 is a top plan view of the closure shown in Fig. 3.

Fig. 5 is a side elevation, partly in section of a 5 further modification of my invention.

Figs. 6, 7, and 8 show another modified form of closure applied to a receptacle, in side elevation, top plan and cross section respectively,

Figs. 9, 10, and 11 are views similar to Figs. 10 6, 7, and 8 respectively of another modified form of my invention, the section in Fig. 11 being taken on the line A—A of Fig. 10.

Fig. 12 is a front elevation, partly in section of a still further modification of my invention, the 15 section being taken on line C—C of Fig. 13.

Fig. 13 is a top plan view of the modified form of the invention shown in Fig. 12.

Fig. 14 is a sectional view of the same, taken on the line A—A of Fig. 13.

Fig. 15 is another sectional view similar to Fig. 14 but taken on the line B—B of Fig. 13.

Figs. 16 and 17 show a top plan view and a front elevational view respectively of still another modified form of closure, the elevational view 25 being partly in section, the section being taken on the line D—D of Fig. 16.

Referring to the drawings in detail, Figures 1 and 2 illustrate in cross-section and side elevation a closure construction in which the tension ring 30 is held in the closed position without additional means. The numeral 1 designates my improved tension ring which is adapted to be mounted on the cover 2 of the container for maintaining said cover in closed position on the wall 3 of the container. Suitable packing 8 may be provided between the cover 2 and the wall 3 of the container. The ends of the tension ring are enlarged by the thickness of the closure members 4 secured thereto on the inside. The closure members 4 consist 40 of double flat strips which may be brought into engagement by any suitable means, not shown. When the ring 1 is fixed on the cover 2, the lug 15 provided on the one closure member slides over the curved guiding surface 4a of the other closure member and thereby forces the members resiliently apart. When the closed position is reached the lug 15 which may be an inserted bolt, snaps automatically into the corresponding opening 15a 45 of the other closure member. The closure is secured partly by means of a recess 15b which prevents loosening of the closure member engaging behind it.

50 In addition the lug 15 has at the projecting end a boring 16 for receiving a seal cord. In Figures 3 and 4 a closure construction is illus- 55

trated in which the one closure member 4 is bent over at the end, the bent over part 21 when the ring is fixed on sliding over the curved guiding surface engaging automatically behind the other closure member 4 and thus holding the tension ring in the closed position. A lug 15 open at the side pressed out of the closure member 4 simultaneously snaps into the opening 20 of the bent over closure member 4. The projecting aperture 19 of the lug receives the seal cord.

Figure 5 shows a closure construction in which both ends of the closure members are bent over. The bent over part 22 of the closure member 4, behind which the bent over part 21 lies, catches in an opening of the other closure member 4 and together with the projecting end of the boring 23 receives a seal cord.

Figures 6, 7, and 8 show in elevation, plan and cross-section a constructional form of the tension ring closure which completely meets all requirements as regards security. The one closure member is again provided with a bent over part 21 which engages behind the other closure member. Both closure members 4 have longitudinal bushings 26 and 27, rolled out of their own material, which in the closed position of the tension ring lie coaxially one in front of the other so that their openings coincide with the boring 24 provided in the bent over part 21, and make it possible to insert the securing pin 28. The latter again has at the projecting end a boring for receiving the seal cord.

It is shown in the constructions according to Figures 3 to 8 how the closure members are reinforced by means of ribs pressed therein so that they can be made from comparatively thin material.

Figures 9 and 10 show a further improved construction.

The end of one closure member carrying the engaging part covers the securing pin within the bushing of the other closure member. For this purpose the bushing of the rear closure member is extended downwardly and is left open at the top as far as is necessary for the engaging part to pass. The closure can then not be opened as long as the securing pin is in the bushing. The pin itself is secured in the known manner by means of a seal. With the construction described it is possible to bend over the engaging part of the one closure member only to an extent corresponding to the thickness of the other closure member. The low projection of the bent over part produces only a small spreading of the closure members in sliding over the opposite part. An undesired deformation of the ends of the ring and a diminution of the spring action of the closure members is particularly avoided.

A further advantage consists in this, that the closure member can be made shorter in the direction towards the middle of the container, which is desirable with regard to the pressing on of the ends of the ring on the edge of the container. Finally, this construction of the closure enables the device to be manufactured more cheaply. Figure 9 shows a front elevation, Figure 10 a plan and Figure 11 a side elevation of the closure. *a* is the tension ring, *b* the cover of the container, *c* the wall of the container and *d* and *d'* the closure members secured to the ends of the ring. The bent over part *e* of the closure member *d'* slides under the oblique surface *f* of the closure member *d* formed by pressing and engages behind this when the closed position is reached, on account of the spring action of the engaging

end. Through the bushings *m* and *n* which now lie side by side, a securing pin *g* is placed which at its free end has a hole *h* for receiving the seal cord. Figure 11 shows how the bushing *m* is left open at the top as far as is necessary for the passage of the bent over part *e*. It is further shown how the engaging part of the closure member *d'* covers the securing part *g*.

According to a further feature of the invention the closure members provided at the ends of the ring are so constructed that in the closed position they take up a shape which makes it possible to fit on a known securing cap. The construction of the closure members is thereby considerably simplified because it becomes unnecessary to provide bushings for a pin. This fact, together with the absence of the sealing parts of the sealing device, causes the cost of manufacture to be considerably reduced. While with the sealing arrangement it is possible that, for example, on account of the damage which may easily occur or on account of skilful manipulation that the closure can be opened by unauthorized persons, this danger is completely avoided by a securing cap constructed in a known manner. The cap secures the closure parts not only against undesired and unauthorized opening, but also on account of the complete enclosing of the engaging closure means, against accidental damage and against other undesired external influences. The closure has a pleasing appearance. The surface of the cap offers the possibility of applying a suitable advertisement.

In the constructional form according to Figures 14-17 the engagement members *f* and *h* are made semicircular in the upper part so that in the closed position they form a complete circle. In order to obtain a suitable abutment for the securing cap *m*, the closure members *d* and *d'* are offset in the form *k*, whereby the semi-circular closing parts *f* and *h* are formed. In addition, the closure parts *f* and *h* have an edge *i* at the height of the parts *e* and *h* which engage one over the other in order to obtain a uniformly thick abutment for the cap *m*. The edge *i* is interrupted only at the place where the part *e*, which engages behind, is led through. In the closed position of the closure, the cap *m* is placed over the closure members *f* and *h* and by means of a closing tool the collar *n* of the cap is drawn together in a known manner under the closure members so that these are secured in the engaging position and against unauthorized handling. The opening of the closure can be effected only after removing the cap *m* by destroying it. Unauthorized handling of the securing cap on account of the notches provided on the edge *n* of the cap would cause it to be destroyed and can therefore be detected.

Figure 15 shows how the edge *i* can be extended in the form *o* so as to bear against the cover *b* of the container which may simplify the closing of the seal. Otherwise this extension *o* may act as abutment against the correspondingly shaped guiding member *p* secured to the cover *b* in order to ensure that the ends of the tension ring will bear firmly against the edge of the container.

Figures 16 and 17 show a further modification of the closure in which the closure member *f* and *h* each have a completely circular shape. This is only interrupted in the closure member *f* at the place where the part *e*, which engages behind the closure member *h* forms the completion. The closure members *f* and *h* thus coincide completely in the closed position. This construction makes

it possible to provide a depression or aperture *q* which makes it possible to puncture the prepared cover surface when removing the seal cap *m*.

It is obvious that in addition to the constructional examples described, further modifications of the closure members are possible without departing from the essence of the invention, which consists in this, that the closure means have a suitable shape for receiving a seal cap. In Figure 13 for example, it is shown in broken lines that the closure members *f* and *h* can have a polygonal shape instead of a circular shape. Even with a rectangular construction of the closure members the application of a suitably shaped sealing cap would make it possible to secure the closure sufficiently.

Having now described my invention, what I claim as new and desire to secure by Letters Patent is:—

20 1. A tension ring closure for packing containers, comprising a tension ring, closure elements projecting from the ends of the tension ring at an angle less than 180° and adapted to engage together when the tension ring is brought into the closed position, and means integral with at least one of said closure elements and detachably engaging the other one of said closure elements for locking the latter in the engaged position.

30 2. A tension ring closure for packing containers comprising a tension ring, closure elements projecting from the ends of the tension ring at an angle less than 180° and adapted to engage together when the tension ring is brought into the closed position, and means integral with at least one of said closure elements and detachably engaging the other one of said closure elements for locking the latter in engaged position, said last mentioned means including an inclined 40 surface on one closure element, an abutment surface terminating the inclined surface, and an engaging part on the other closure element adapted to slide along the inclined surface and engage with the abutment surface.

45 3. A tension ring closure for packing containers, comprising a tension ring, closure elements projecting from the ends of the tension ring at an angle less than 180° and adapted to engage together when the tension ring is brought into the closed position, and means forming a permanent part of at least one of said closure elements and having detachable snap engagement with the other one of said closure elements for locking the latter in the engaged position.

55 4. A tension ring closure for packing containers, comprising a tension ring, closure elements projecting from the ends of the tension ring at an angle less than 180° and adapted to engage together when the tension ring is brought into the closed position, and means forming a permanent part of at least one of said closure elements and having detachable snap engagement with the other one of said closure elements for locking the latter in the engaged position, at least one of said closure elements having an inclined guiding surface for guiding said means into snap engagement with the closure members.

5. A tension ring closure for packing containers, comprising a tension ring, closure elements projecting from the ends of the tension ring at an angle less than 180° and adapted to engage together when the tension ring is brought into the closed position, and means forming a permanent part of at least one of said closure elements and having detachable snap engagement

with the other one of said closure elements for locking the latter in the engaged position, the last mentioned closure element having an aperture and an inclined guiding surface for guiding said means into snap engagement with said aperture. 5

6. A tension ring closure for packing containers, comprising a tension ring, closure elements projecting from the ends of the tension ring at an angle less than 180° and adapted to engage together when the tension ring is brought into the closed position, and means forming a permanent part of at least one of said closure elements and having detachable snap engagement with the other one of said closure elements for locking 15 the latter in the engaged position, the last mentioned closure element having an aperture, and said means including a bolt extending into said aperture, said bolt being recessed and adapted to engage the wall of said aperture for normally 20 maintaining said bolt in engagement with said apertured element.

7. A tension ring closure for packing containers, comprising a tension ring, closure elements projecting from the ends of the tension ring at an angle less than 180° and adapted to engage together when the tension ring is brought into the closed position, and means forming a permanent part of at least one of said closure elements and having detachable snap engagement with the other one of said closure elements for locking the latter in the engaged position, said last mentioned means including a flange on the end of one of said elements and extending substantially 30 at right angles to the plane of said elements. 35

8. A tension ring closure for packing containers, comprising a tension ring, closure elements projecting from the ends of the tension ring at an angle less than 180° and adapted to engage together when the tension ring is brought into the closed position, and means forming a permanent part of at least one of said closure elements and having detachable snap engagement with the other one of said closure elements for locking the latter in the engaged position, said last mentioned means including a flange on the end of one of said elements, extending at substantially right angles to the plane of said elements, and abutting against the end of the other closure member, at least one of said closure elements having an inclined guiding surface for guiding the flange on the end of one of said elements into abutting relation with the end of the other closure element. 45 50

9. A tension ring closure for packing containers, comprising a tension ring, closure elements projecting from the ends of the tension ring at an angle less than 180° and adapted to engage together when the tension ring is brought into the closed position, and means forming a permanent part of at least one of said closure elements and having detachable snap engagement with the other one of said closure elements for locking the latter in the engaged position, each of said elements being provided with a substantially tubular portion, and means arranged within said tubular 60 portions for locking said first means in engagement with the closure element, and preventing displacement of one element relatively to the other. 65

10. A tension ring closure for packing containers, comprising a tension ring, closure elements projecting from the ends of the tension ring at an angle less than 180° and adapted to engage together when the tension ring is brought into the closed position, and means

- 5 forming a permanent part of at least one of said closure elements and having detachable snap engagement with the other one of said closure elements for locking the latter in the engaged position, each of said elements being provided at its inner edge with a substantially tubular portion, an elongated member extending through said tubular portions for preventing displacement of one element relatively to the other element, and means for locking said member in position within said tubular portion.
- 10 11. A tension ring closure for packing containers comprising a tension ring, closure elements projecting from the ends of the tension ring at an angle less than 180° and adapted to engage together when the tension ring is brought into the closed position, and means integral with at least one of said closure elements and detachably engaging the other one of said closure elements for locking the latter in engaged position, said last mentioned means including an inclined surface on one closure element, an abutment surface terminating the inclined surface, and an engaging part on the other closure element

15 adapted to slide along the inclined surface and engage with the abutment surface, said engaging part, inclined surface and said abutment surface forming a substantially circular member.

12. A tension ring closure for packing containers comprising a tension ring, closure elements projecting from the ends of the tension ring at an angle less than 180° and adapted to engage together when the tension ring is brought into closed position, means forming a permanent part of at least one of said closure elements and having detachable snap engagement with the other one of said closure elements for locking the latter in the engaged position, one of said closure elements having an inclined guiding surface for 15 guiding said means into snap engagement therewith, an abutment terminating said inclined surface, said means including a projecting lug on the other closure element adapted to slide along said inclined surface into engagement with said abutment, said abutment, lug, and inclined surface forming a substantially circular member.

KARL WILHELM MAUSER.
